[57] CLAIM

The ornamental design for an electric generator, as
shown and described.

DESCRIPTION

FIG. 1 is a perspective view of an electric generator
showing my design;

FIG. 2 is a perspective view thereof, with the handle
shown in raised position;

FIG. 3 is a front elevational view thereof;

FIG. 4 is a back elevational view thereof;

FIG. 5 is a top plan view thereof;

FIG. 6 is a left side elevational view thereof; and

FIG. 7 is a right side elevational view thereof.
